 Faximile, Inc., New York, N. Y., a corporation
 of New York

Application May 22, 1942, Serial No. 444,005

9 Claims. (Cl. 178—7.1)

The present invention concerns facsimile pick-up scanners.

One object of the present invention is to provide a simple and efficient facsimile pick-up scanner capable of scanning copy in continuous sheets or in short lengths and in any width up to a pre-determined maximum.

Another object is to provide a simple and efficient illuminating system for scanning the copy.

A further object is to provide even illumination in conjunction with a simple photo-electric cell pick-up system.

A still further object is to provide a simple and efficient motor drive for the scanner drum.

These and other objects of the invention will be apparent from the detailed description of the invention given in connection with the various figures of the drawing.

In order to transmit copy by wire line or radio for facsimile purposes signals representing the light and shade of the copy are usually generated by scanning the copy point by point. A concentrated light beam is usually directed upon the copy and the light reflected from an elemental area utilized to actuate a photoelectric cell. Such a system utilizes only a small fraction of the available light due to the inefficiency of conventional lens systems and to the low coefficient of reflection of most copy. Another difficulty is encountered in scanning a long sheet of copy and most systems which are capable of doing this are very complicated.

The present invention utilizes light transmitted through the copy, usually a paper sheet, and it has been found to be a simple and efficient method. In scanning by transmitted light a simple and efficient light system consists in a lamp with a long filament. Scanning is accomplished at the intersection of a helical slit in a rotating drum and a linear stationary slit. The inside of the drum is silvered or painted white to reflect a large percentage of the light entering the scanning aperture into two photo-electric cells mounted at the ends of the drum. Conventional photo-electric cells are used, eliminating difficulties arising from variable sensitivity along the length of a long photo-electric cell. Small variations in illumination along the scanning line are compensated by means of a variable density wedge or by making the linear slit slightly wider near its center. Almost any length of copy may be scanned in the present device by means of a simple sheet feeding mechanism. Copy of any width up to the length of the drum may be utilized.

In the drawing:

Fig. 1 shows a general view of one form of the present invention cut away to show some details.

Fig. 2 shows an end view of the form of the invention shown in Fig. 1.

Figs. 3, 4 and 5 show various details and modifications of the present invention.

Figs. 6 and 7 show light distribution diagrams useful in explaining the operation of the invention.

Fig. 1 shows one form of the present invention in which a cylindrical drum 1 having hollow end shafts 41 and 42 is mounted in end bearings 3 and 2 carried by bed-plate 4. Drum 1 is rotated by a motor comprising stator 45 directly attached to, or an integral part of, shaft 41 and stator poles 43 and 44. Also carried by bed-plate 4 are brackets 5 and 6 supporting photoelectric cells 13 and 17 by means of support arms 14 and 8. Photo-electric cells 13 and 17 are mounted inside drum 1 at or near its ends. Cell 13 includes cathode 18 and anode 17 and is connected to signal utilization apparatus by means of leads 15 and 16. Cell 17 includes cathode 12 and anode 11 and is connected to signal utilization apparatus by means of leads 9 and 10. Drum 1 is preferably formed of an opaque material, such as metal, and is silvered and polished or painted white on its inside surface. Thru the walls of drum 1 is cut a helical slit 19 passing substantially once around the circumference. The scanning of copy is accomplished by rotating drum 1 at a constant speed by means of motor 43—44—45, so that slit 19 moves repeatedly along an intersecting linear slot to be described later.

Fig. 2 shows an end view of the scanner shown in Fig. 1 showing the relation of drum 1, photo-electric cell 13 and slit 19 to the remainder of the scanning apparatus. Either continuous copy 20 as shown passing from roll 21 to roll 28 may be scanned or short pieces of copy may be fed into the scanning apparatus by placing them on feed plate 40. The copy to be scanned is fed downward by feed rollers 29 and 30 between guide plates 21—22—24 and on between ejection rollers 31—32. The copy is illuminated by means of lamp 25 having a long straight filament 26. The light from filament is concentrated by means of an optical system, such as reflector 39. The illumination of the copy is confined to a narrow line by means of aperture plate 37—38. Further confining of the light may be produced by apertures in plates 23, 21—22 or both. The intersection of helical slot 19 with the linear aperture forms the scanning element which moves

across the copy. The scanning is completed by the downward motion of the copy.

By making aperture plate 21-22 curved, and with the slit edges so thin as to be practically knife-edged, the copy may be passed over it and in contact with it at the linear aperture line. This contacting of the copy with the aperture accurately determines the scanning plane so that the image of lamp filament 26 may be accurately focused. Both the contact with the aperture and the fixing of the plane result in extremely fine definition of the scanning element as it moves across the copy. Thus, fine detail may be obtained in scanning the copy with a simple and efficient scanning device.

Pick-up of the light from the scanning process is carried out by means of a suitable photo-electric cell within drum 1. While a long photo-electric cell may obviously be used, it has been found more practical to use one or two conventional cells mounted near the ends of the drum as shown in Fig. 1. By slivering or painting white the inside of drum 1, practically all the light entering thru the scanning aperture and passing the helical slot 19 is reflected into cells 7 and 13 resulting in high efficiency and even illumination along the linear scanning path.

If it is found that there is still a somewhat lower intensity of light at the center of the scanning path, as illustrated by the shade lines in Fig. 7, an aperture admitting more light at its center, as shown in Fig. 3, may be used. The compensating aperture between plates 21 and 22 has equal widths at its ends A and C while it is made wider at the center b to compensate the falling off of effective illumination which results when the scanning aperture is near the center of its travel. Fig. 3 is exaggerated, since, in general, the center portion need be made only slightly wider than the ends.

In the case of short drums or where less detail is required, one photo-electric cell may be used, as shown in Fig. 6, in which case the illumination falls toward the end away from the cell, as shown. The light distribution may be compensated in this case by means of an aperture which is made wider as it goes away from the cell, as shown in Fig. 5.

While the aperture between plates 21 and 22 is shown as the compensating aperture, it will be evident that the compensation may be applied to the other apertures, e. g. 23-24, or that other means, such as a variable density wedge, or a lamp having varying light output along its length, may be used to accomplish the same thing, without loss of resolution.

Fig. 4 shows lamp 25 having a long filament 26, and seals 33 and 35 and leads 34 and 36. Filament 26 may be coiled as shown or a straight wire as long as it gives a concentrated linear illumination of a narrow effective width.

Motor 43-44-45 comprising field coils 43-44 and rotor 45 integral with or mounted directly on shaft 41 is simple and efficient and provides an accurate smooth drive for drum 1.

The scanning system above described is also useful for recording facsimile signals. In recording, cells 7 and 13 are signal modulated glow lamps and sheet 20 is a light sensitive record sheet, such as a sheet coated with a photographic emulsion.

While one embodiment and a few modifications have been shown and described, it will be evident to those skilled in the art that many modifications may be made within the spirit and

scope of the invention as set forth in the appended claims.

What is claimed is:

1. In a facsimile scanner the combination of, a scanning drum including a helical slot, a pair of photo-electric cells, means for mounting said cells near the ends and inside said drum, a linear slot formed between two curved plates and adjacent said drum, means for moving a copy sheet to be scanned over said curved plates, a linear light source for illuminating said linear aperture through said copy, and means for rotating said drum to linearly scan said copy at the intersection of said helical and linear apertures.
- 15 2. In a facsimile scanner the combination of, a rotatable drum carrying a helical aperture, a curved plate cut to form a linear aperture progressively wider along at least a portion of its length for forming an aperture of varying cross-section with said helical aperture, as said drum is rotated, means for moving a copy sheet to be scanned past said apertures, and means for evenly illuminating said sheet at least along a line immediately over said linear aperture.
- 20 3. In a facsimile scanner the combination of, a scanning device including a drum and a stationary plate, means comprising a helical slot in said drum and a closely superimposed linear aperture in said plate forming a scanning aperture, and means for moving a copy sheet at a uniform rate past said linear aperture.
- 25 4. In a facsimile scanner the combination of, a scanning device including a rotatable drum and a stationary plate, means comprising a helical slot in said drum and a closely superimposed linear aperture of varying width in said plate forming a scanning aperture, and means for moving a copy sheet at a uniform rate past said linear aperture.
- 30 5. In a facsimile scanner the combination of, a rotatable drum carrying a highly reflecting inside surface and a helical slot through its surface, a pair of photo-electric cells, means for mounting said cells inside said drum adjacent its ends, a linear aperture plate closely adjacent to the outside surface of said drum, means for moving a copy sheet past said plate and substantially in contact with it at least in the region of the aperture, and means for illuminating said sheet at least in the region of said aperture.
- 35 6. In a facsimile scanner, the combination of, a rotatable drum, a pair of photo-electric cells mounted near the ends and inside said drum for generating signals in accordance with light entering said drum, a highly reflecting surface on the inside of said drum for reflecting light entering said drum into said photo-electric cells, a helical aperture through the surface of said drum for partially defining a scanning aperture, means for defining a linear aperture closely superimposed upon said drum to complete the defining of the scanning aperture, means for drawing copy to be scanned across said two apertures, means for directing light on to the copy on the side opposite the aperture, means for rotating said drum to cause said scanning aperture to pass successively across said copy to complete the scanning process, and utilization means connected to said photo-electric cells for utilizing the signals generated by the scanning process.
- 40 7. In a facsimile scanner, a rotatable drum having a narrow helical slot, and a stationary plate having a longitudinally extending narrow slot arranged close to the surface of the drum, a translating device within the drum, the point of

intersection of the two slots constituting a scanning aperture and means for moving a copy sheet past said aperture.

8. In a facsimile scanner, the combination of, a rotatable drum, means inside said drum for generating signals in accordance with light entering said drum, said drum having a helical aperture through the surface of said drum for partially defining a scanning aperture, means for defining a linear aperture closely superimposed upon said drum to complete the defining of the scanning aperture, means for drawing copy to be scanned across said two apertures, means for rotating said drum to cause said scanning aper-

ture to pass successively across said copy to complete the scanning process, and utilization means for utilizing the signals generated by the scanning process.

5 9. In a facsimile scanner, a rotatable drum having a narrow helical slot, and a stationary plate having a longitudinally extending narrow slot arranged close to the surface of the drum, a light source within the drum, the point of intersection of the two slots constituting a scanning aperture and means for moving a light-sensitive sheet past said aperture.
